UNITED STATES PATENT OFFICE.

STEPHEN D. BAKER, OF NEW YORK, N. Y.

DESIGN FOR A WALL-RECEPACLE FOR SOAP AND OTHER TOILET ARTICLES.

51,405.

Specification for Design.

Patented Oct. 23, 1917.

Application filed July 17, 1917. Serial No. 181,179. Term of patent 14 years.

To all whom it may concern:

Be it known that I, STEPHEN D. BAKER, a citizen of the United States, residing at New York city, in the county of New York and State of New York, have invented a new, original, and ornamental Design for a Wall-Receptacle for Soap and other Toilet Articles, of which the following is a specification, reference being had to the accompanying drawing, forming part thereof.

The figure is a front elevation of a wall receptacle illustrating my new design.

I claim:

The new and ornamental design for a wall receptacle for soap and other toilet articles, substantially as herein shown.

In testimony whereof, I affix my signature.

STEPHEN D. BAKER.
